COMBINED SPOON, SPATULA, AND BLENDER

Lawrence K. Carroll, 1118 Birchard Ave.; Joseph H. Messinger, 219 N. Wayne; and Charles D. Whitecomb, 1141 Hickory St., all of Fremont, Ohio

Filed Dec. 11, 1959, Ser. No. 58,631

Term of patent 14 years

(Cl. D44—29)

FIG. 1 is a top plan view of the combined spoon, spatula, and blender of this invention, with a handle therefor being shown in dashed lines;

FIG. 2 is a side elevational view of the combined spoon, spatula, and blender of FIG. 1;

FIG. 3 is a blade end view of the combined spoon, spatula, and blender of FIGS. 1 and 2; and

FIG. 4 is a cross-sectional view taken along line IV-IV of FIG. 1.

The dominant features of my design reside in the portions shown in full lines.

We claim:

The ornamental design for a combined spoon, spatula, and blender, as shown and described.
